United States Patent Office.

JOHN H. WHISSEMORE, OF MANSFIELD, OHIO.

Letters Patent No. 81,041, dated August 11, 1868.

IMPROVED HARNESS-TREE.

The Schedule referred to in these Letters Patent and making part of the same.

TO ALL WHOM IT MAY CONCERN:

Be it known that I, JOHN H. WHISSEMORE, in the city of Mansfield, county of Richland, State of Ohio, have invented a new and improved Harness-Tree; and I do hereby declare that the following is a full, clear, and exact description of the construction of the same, reference being had to the annexed drawings, making a part of this specification, in which—

Figure 1 is a perspective view.

Figure 2 is an exterior or plan view.

Figure 3 is an interior or under side view.

Figure 4 is a sectional view through the centre of the tree.

The nature of my invention consists in forming a harness-tree, of either cast or malleable iron, when the same has a raised flange or lip arranged around its inner edges or sides for the reception of the pad, said flange or lip being provided with a bearing-plate, and extending sufficiently far beyond the upper frame to afford a suitable groove or recess for the introduction of the tug-straps.

The tree thus formed can be rendered most durable, as well as highly ornamental, by covering the same with silver-plate, or subjecting it to the well-known japanning process. This will add little or nothing to the cost of the tree, and, as it obviates entirely the necessity of covering the same with leather, a beautiful and serviceable article is produced at less cost than according to any of the plans or methods now generally used.

To enable others skilled in the art to make and use my invention, I will now proceed to describe its construction and operation.

A is the top or frame of the tree, and is provided on its under side with lips or flanges, $a' a'$. Between these lips or flanges $a' a'$ is formed the groove a . Within this groove a is fastened, by any suitable means, the ordinary harness-tree pad.

The lips or flanges $a' a'$ extend a short distance beyond the surface of the top or frame A, and have a bearing-plate, b' , attached to their under sides.

This plate b' extends a short distance beyond the end of the top or frame A, thus leaving an opening, c , through which passes the tug-strap.

The tug-strap has its bearing in the exterior groove or recess $b b$ formed by flanges on the plate b' .

The top or frame A is cast or formed with numerous holes, $d d$, through which pass the terret-rings, and also the necessary screw-shanks or other screw-bolts used in securing the pad and tug-strap to the frame A.

The entire tree, with its grooves or openings, lips or flanges, is formed of cast or malleable iron, and in one piece.

The top or frame, and side lips or flanges can be japanned or covered with silver-plate.

Having thus fully described my invention, what I claim therein as new, and desire to secure by Letters Patent of the United States, is—

The harness-tree A and plate b' , when the same are provided with lips or flanges, and so combined and arranged as to form the opening c , and a continuous groove, $a b$, for the pad and tug-strap, said groove extending in both directions beyond the plate of the tree, as described, and for the purpose specified.

JOHN H. WHISSEMORE.
